DRY THREAD GUIDE

William Renschak, Philadelphia, Pa.

Application January 10, 1936, Serial No. 58,502

15 Claims. (Cl. 242—157)

This application is a continuation in part of application Serial No. 626,055 filed July 29, 1932.

This invention relates to dry thread guides for textile knitting machines and has for its object the provision of a new and improved guide.

The general practice in the art prior to my invention has been to use a rolled piece of felt as a dry thread guide. The felt to be used for this purpose was rolled into a cylinder and placed 10 into the guide box. To get the proper tension the felt had to be raised or lowered. However, this setting was always affected by the vibration of the machine and/or the tension of the thread with resultant deleterious effects on the fabric and 15 loss of time by the knitter. In addition knots in the threads get snagged or caught in the felt causing the thread to break thereby resulting in additional loss of time by the knitter.

More particularly stated it is an object of this 20 invention to produce a dry thread guide wherein all of the above objections will be obviated.

Another object of this invention is to produce a dry thread guide wherein the tension of the 25 thread may be readily varied.

Another object of this invention is to produce a dry thread guide which is adapted to be carried by the guide box and which will maintain its position in said guide box without the 30 use of springs.

Another object of this invention is to produce a dry thread guide wherein the tendency of the 35 thread to jump from the tension posts is reduced to a minimum.

Another object of this invention is to produce a dry thread guide which is simple in construction, 40 easy to manufacture and produce, and which will not necessitate the addition of elements to the knitting machines now in use for the purpose of either supporting or carrying my novel device.

The above as well as other objects of this invention and the advantages arising therefrom will be obvious from the following description and the 45 drawing which form a part thereof.

In the drawing Figure 1 is a top view showing 50 my thread guide in position upon the supporting bar of a full fashioned knitting machine.

Figure 2 is a section taken along the line 2—2 of Figure 1.

Figure 3 is a section taken along the line 3—3 55 of Figure 1.

Figure 4 is a perspective view of my improved thread guide associated with a somewhat larger retaining spring than that shown in Figures 1, 2 and 3.

Figure 5 is a top view taken similarly to Figure

1 and showing a modification of the thread guide shown in Figure 1. The different types of lines show alternative positions of the thread.

Figure 6 is a section taken along the line 6—6 of Figure 5. 5

Figure 7 is a view looking along the line 7—7 of Figure 5 of the thread carrier shown in Figure 5 dissociated from the cup.

Figure 8 is a section taken similarly to Figure 6 of a modification of the thread guide shown 10 in Figure 5.

Referring more particularly to the drawing wherein similar reference numerals and reference letters denote similar parts, reference letter B denotes the supporting bar of a full fashioned 15 hosiery machine upon which the usual tension box or thread guide receiving pocket P is suspended by means of the inverse hook 4. The pocket P has the usual main body member 1 consisting of the cylindrical wall 2, the flat ends 3 20 and the bar engaging hook 4. The bar B and pocket P are well known in the art and constitute a part of any full fashioned hosiery knitting machine such as, for instance, are manufactured by the Reading Machine Company. Further, 25 these elements in and of themselves do not form a part of my invention and for that reason will not be here further described.

Positioned within the pocket P is my novel 30 thread carrier and tension member C shown in Figures 1 to 4 inclusive, or the novel thread carrier and tension member D shown in Figures 5 and 6, or the novel thread carrier and tension member E shown in Figure 8.

The thread carrier and tension member C is 35 composed of side walls 5 connected at their lower ends by the spring receiving cylinder 7 and at their upper end in the roof member 15 which is surmounted by the smooth curved thread bearing member 6. The roof member 15 is spaced 40 apart from the member 7 leaving the aperture 10. This makes the ensemble lighter.

The spring receiving cylinder 7 has a spring receiving bore 8 formed therein and has the double function of a rib or stiffening member for the 45 walls 5 and as a carrier for the spring 9.

The member 15 has the cutout portions 17 formed therein and serves both as a rib or stiffening member for the walls 5 and as a carrier or base for the thread bearing member 6. 50

The thread bearing member 6 has a curved glazed upper thread contacting surface 11 on which are formed the auxiliary tension hooks or posts 12 each of which consists of an upwardly 55 extending base 13 terminating in a horizontally

extending arm 14. The member 6 terminates at its lower end in a substantially rectangular base as shown. The member 6 is of such size and so positioned upon the member 15 that it leaves the shoulders 16 on the member 15 and extends beyond the inner walls 20 of the cutout portion 17 over the entire distance between the tension posts 12 as is clearly shown in the drawing. Conversely stated the cutout portion 17 must be so formed that its inner wall 20 will fall within the ends 19 of the member 6 for the entire distance between the tension posts 12. This structure has the double effect of lessening the weight of the ensemble and insuring that the thread T will not contact with any portion of the carrier C except the glazed member 6.

The carrier C is so proportioned that when inserted in its position in the pocket P a substantial portion of the element 6 will be above the wall 2 of the pocket P as is clearly shown in Figures 2 and 3. In its preferred position when in use the thread guide rests upon and is supported by the floor 22 of the tension box P. In Figures 2 and 3 the lower end 21 of the thread guide is shown as somewhat above the floor 22 of the tension box and the clearance between the walls of the tension box and the walls of the thread guide have been exaggerated for the purpose of greater clearness of illustration. The actual condition of the element C when in use is to be considered as that shown for the element D in Figure 6, wherein the clearance between the side walls 48 of the member D and the walls 49 of the pocket P has been exaggerated for the purpose of clearness.

Although the manner of using my improved device is believed to be obvious from the foregoing description yet to obviate any possibility of a misunderstanding the following detailed description is here given:

We start with the ensemble such as shown in Figure 4 with the thread carrier C outside of its pocket and having the spring 9 positioned in the spring receiving bore 8. The ensemble is now inserted into the pocket P in such a manner that its lower end 21 rests upon the floor 22 of the pocket P. The spring 9 is of such construction that when not under tension its length is less than the distance between the downwardly converging walls 3 of the pocket P at the upper end 50 of the pocket but more than the distance between these walls at the point where the spring contacts with them when the thread carrier is in the operative position shown in Figures 2 and 3. Because of this structure the walls 3 serve as cams and serve to place the spring 9 under compression as the carrier C is inserted in place. The thread T coming from the bobbin is now strung so that it runs over the surface 11 of the carrier 6 in the position shown by the full lines in Figure 1. If greater tension is desired the thread T is positioned to take the course T₁ (shown by the dot and dash lines in Figure 1) wherein it winds around a single tension post 12. If still greater tension is desired the thread T is positioned to take the course T₂ (shown by the double-dot and dash lines in Figure 1) wherein the threads wind around both tension posts 12 on their way to the snappers.

The thread carrier D differs from the carrier C in the following particulars:

(1) The body member 25 having the spring receiving bore 26 formed therein has been substituted for the body member consisting of the portions 5, 7 and 15.

(2) The thread bearing member 27 has been substituted for the thread bearing member 6.

(3) The tension ridge 29 has been substituted for the tension posts 12.

The tension ridge 29 has the thread guiding and tension apertures 30 and 31 formed therein. The apertures 31 differ from the aperture 30 in that a channel 32 connects the apertures 31 with the surface 33 of the tension ridge whereas the aperture 30 is closed to the said surface 33. The closed aperture 30 reduces to a minimum the tendency of the thread to jump from the tension posts when the tension is released, which occurs when the machine stops. The apertures 30 and 31 serve to define and form the tension posts 34, 35, 36 and 37.

Definition: The term "tension posts" as used in the specification and claims is to be understood as including the posts 12 (Figures 1 to 4), 34, 35, 36, 37 (Figures 5 and 6), 44, 45, 46, 47 (Figure 7), and their equivalents.

The thread carrier E differs from the carrier D only in the following particulars:

(1) The tension ridge 40 has a greater number of apertures 31 formed therein.

(2) The tension ridge 40 is longer than the ridge 29 and has outwardly inclined edges 41 instead of the inwardly inclined edges 37 in order to permit the formation of the additional apertures 31. (The tension posts 44, 45, 46 and 47 are the equivalents of the tension posts 34, 35, 36 and 37 respectively.)

The thread carriers D and E are inserted into the pocket P so that their respective lower edges 38 and 42 rest upon the floor 22 of said pocket.

As is shown in Figure 6 the carriers D or the carriers C and E may be placed in the pocket P without the use of the spring 9 or 9a. In such event the weight of the carriers is sufficient to keep the carriers in their proper positions in the cups. Since the carriers are rigid and are resting on the floor 22 of the pocket P neither vibration of the machine nor the downward component of the force due to the tension of the thread T will cause the carriers to sink within the cups as occurs with the felts formerly in use. Instead, the carriers will always remain in the same position.

Where it is found that the cups are too deep for the carriers it is only necessary to raise the floor of the pocket P by placing thereon a wad of paper or other non compressible material.

The plural number of apertures and tension posts enable me to vary the path of the thread and therefore its tension. In Figure 5 the lines T₃, T₄ and T₅ denote alternative paths of varying tension for the thread T. I prefer to use a path such as T₃ or T₅ through the closed ring aperture 30 since the tendency of the thread to jump from the tension posts when the tension is released is reduced to a minimum when the thread traverses a path through said aperture 30.

The above disclosure is to be understood as being by the way of illustration only and not by the way of limitation since many changes may be made in the devices herein shown without departing from the spirit of my invention which in one of its aspects consists in providing a dry thread guide with a nonyielding smooth thread contacting surface and forming and positioning the guide so that it will not be substantially affected by the vibration of the machine. In another of its aspects it consists in providing said novel thread guide with thread tension posts having smooth thread contacting surfaces formed thereon. In another of its aspects it consists in

5 forming one of said tension posts in the form of a closed ring or eye. The changes may include the substitution of equivalents for some or all of the component parts of the device herein disclosed; or changes in relative size of the parts or in the materials used; or in the omission of some of my novel concepts from the device. For instance, vertical walls may be substituted for the converging walls of both the pocket and thread 10 carrier shown in Figures 1 to 7 inclusive. Or, if desired, the members C, D and E may be attached directly to the bar B. I prefer at present to construct the carrier C with the portions 5, 7, 15, 25 and 41 of unglazed porcelain surmounted by the 15 porcelain portion 6, 21, or 40 having the glazed porcelain thread contacting surface 11 or 28, from which extend the glazed porcelain tension posts 12, or 34 to 37, or 44 to 47. For the porcelains herein used other materials may be substituted. 20 In all such cases it is necessary to use some non-yielding material as a base for a thread contacting portion which presents a smooth and comparatively hard surface to the thread T and will not materially abrade the thread or be affected 25 by it.

In addition to the variations in structure herein outlined many others will suggest themselves to workers in the art in the light of my disclosure. For this reason it is my desire that the claims 30 which are hereunto appended for the purpose of defining my invention should be limited only by the prior art.

I claim:

1. A dry thread guide for use in textile machines 35 consisting of the combination of a cup like bearing member; a thread carrier of nonyielding material having a spring receiving bore formed therein removably positioned within said cup like member extending upwardly above the lips of said 40 cup like member, and terminating in a smooth thread contacting surface from which a plural number of tension posts extend; and a helical spring positioned within said bore and contacting with the walls of said cup like member to hold 45 said thread carrier in any desired position with respect to said bearing member.

2. A dry thread guide for use in textile machines comprising the combination of a cup like bearing member, a thread carrier carried by the 50 said bearing member, the said thread carrier consisting of two upwardly extending walls connected at one of their ends by a rib having a cylindrical spring receiving bore formed therein and at the other end by a rib terminating in a smooth curved 55 thread bearing surface, and a helical spring carried within the said spring receiving bore and contacting with the walls of the said bearing member for holding the said thread carrier in any position desired with respect to the said bearing 60 member.

3. A thread guide for use in textile machines comprising the combination of a cup like bearing member, a thread carrier carried by the said bearing member, the said thread carrier consisting of two upwardly extending walls connected at one of their ends by a rib having a spring receiving bore formed therein and at the other end by a rib terminating in a smooth curved thread bearing 65 surface having one or more tension posts extending therefrom, and a helical spring carried within the said spring receiving bore and contacting with the walls of the said bearing member for holding the said thread carrier in any position desired with respect to the said bearing member.

75 4. A dry thread guide for use in textile ma-

chines consisting of the combination of a cup like bearing member; a dry thread carrier of nonyielding material having a spring receiving bore formed therein removably positioned within said cup like member, extending upwardly above the 5 lips of said cup like member, and terminating in a smooth thread contacting surface from which extends a tension ridge having one closed ring and a plurality of open ring thread apertures formed therein; and a helical spring positioned 10 within said bore and contacting with the walls of said cup like member to hold said thread carrier in any desired position.

5. As an article of manufacture a dry thread carrier for use in textile machines consisting of 15 a rigid body member having a smooth thread contacting surface formed thereon and a cylindrical spring receiving bore formed therein; and a helical spring carried within and extending from the 20 said spring receiving bore.

6. As an article of manufacture a dry thread carrier for use in textile machines consisting of a rigid body member having a smooth thread contacting surface formed thereon and a spring receiving bore formed therein, one or more tension 25 posts extending from the said thread contacting surface and a helical spring carried within and extending from the said spring receiving bore.

7. As an article of manufacture a dry thread carrier for use in textile machines consisting of 30 two rigid porcelain walls one of the ends of which are connected by a porcelain rib having a cylindrical spring receiving bore formed therein and the other of the ends of which are connected by a porcelain rib having a glazed, smooth thread 35 contacting surface formed thereon, a plurality of glazed, smooth tension posts extending from the said thread contacting surface and a helical spring carried within and extending from the said 40 spring receiving groove.

8. As an article of manufacture a dry thread carrier for use in textile knitting machines consisting of two rigid walls connected at one of their ends by a rib having a spring receiving bore 45 formed therein and at their upper ends by a rib terminating in a smooth thread contacting surface and one or more tension posts extending outwardly from the said thread contacting surface.

9. A dry thread guide for use in textile machines 50 consisting of the combination of a cup like bearing member and a dry thread carrier of nonyielding material removably positioned in said cup like member, extending upwardly above the lips of said cup like member, and terminating in a 55 smooth thread contacting surface from which extends a tension ridge having one closed ring and a plurality of open ring thread apertures formed therein.

10. As an article of manufacture a dry thread 60 carrier for use in textile machines comprising a body member of nonyielding material having a smooth thread contacting surface formed thereon and a spring receiving bore formed therein; and a tension ridge having one closed ring and 65 a plurality of open ring smooth thread apertures formed thereon extending upwardly from said thread contacting surface.

11. A dry thread guide consisting of the combination of a cup like bearing member, a thread 70 carrier having a smooth thread contacting surface positioned within the said bearing member with the thread contacting surface extending beyond the lips of said cup, and means carried by the said thread carrier and contacting with the 75

said bearing member to hold the said thread carrier in any desired position relative to the said bearing member.

12. A dry thread guide consisting of the combination of a cup like bearing member, a thread carrier having a smooth thread contacting surface positioned within the said bearing member with the thread contacting surface extending beyond the lips of said cup; and resilient means carried

10 by the said thread carrier and contacting with the said bearing member to hold the said thread carrier in any desired position relative to the said bearing member.

13. A dry thread guide consisting of the combination of a cup like bearing member, a thread carrier having a smooth thread contacting surface positioned within the said bearing member with the thread contacting surface extending beyond the lips of said cup; and resilient means carried

15 by one of said members for contacting with the other of the said member to hold the said thread carrier

in any desired position relative to the said bearing member.

14. A dry thread guide for use in textile machines consisting of the combination of a cup like bearing member and a thread carrier of nonyielding material removably positioned within and upon the floor of said cup like bearing member, extending upwardly above the lips of said cup like member, and terminating in a plural number of tension posts.

15. A dry thread guide for use in textile machines consisting of the combination of a cup like bearing member and a thread carrier of nonyielding material removably positioned within and

15 upon the floor of said cup like bearing member, extending upwardly above the lips of said cup like member, and terminating in a smooth thread contacting surface from which a plural number of tension posts extend.
